Primary Examiner — Rhea Shields(74) *Attorney, Agent, or Firm* — Mintz Levin Cohn Ferris Glovsky and Popeo, P.C.**CLAIM**

The ornamental design for a surgical robot arm, as shown and described.

DESCRIPTION

FIG. 1 is a top, right-side, front perspective view of a surgical robot arm;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

In the drawings, the broken lines are for the purpose of illustrating portions of the surgical robot arm that form no part of the claimed design.

1 Claim, 7 Drawing Sheets(56)
